WAX INJECTION MACHINE FOR CASTING PROCESSES OR THE LIKE

Vernon F. Antoine, Whittier, Calif., assignor to Coastal
Dynamics Corporation, a corporation of California

Filed Nov. 9, 1961, Ser. No. 67,437

Term of patent 14 years

(Cl. D55—1)

FIG. 1.

FIG. 2.

FIG. 3.

FIG. 4.

FIG. 5.

FIGURE 1 is a front perspective view of a wax injection machine for casting processes or the like showing my new design;

FIGURE 2 is a bottom plan view thereof;

FIGURE 3 is a rear elevational view thereof;

FIGURE 4 is a side elevational view thereof; and,

FIGURE 5 is a top plan view thereof.

The dominant features of my design reside in the portion shown by the solid lines.

I claim:

The ornamental design for a wax injection machine for casting processes or the like, as shown and described.
